UNITED STATES PATENT OFFICE.

CLARENCE C. SCOTT, OF PARIS, TENNESSEE.

CAR REPLACER.

Application filed October 26, 1927. Serial No. 228,894.

The present invention relates to car replacers or rerailers and the primary object of the invention is to provide a rerailer embodying novel features of construction 5 whereby the wheels of rolling stock may be readily replaced upon the rails.

A further object of the invention is to provide a rerailer which is applicable to either side of the rail for replacing the 10 wheels of rolling stock, and embodies a novel arrangement of guide grooves whereby the wheels will be positively guided to a position upon the tread surfaces of the rails without liability of the wheels slipping from 15 the rails after being elevated into position by the rerailers.

A further object of the invention is to provide a rerailer, two of which when properly associated with a pair of rails will so 20 co-act with one another as to guide the wheels of the rolling stock into position upon the rails without allowing the wheels to drop upon the rails with the likelihood of possibly breaking the wheels or resulting in 25 broken trucks or contents of the car.

A further object of the invention is to provide an improved rerailer which is of such construction as to allow for pairs of the devices to be of identical construction 30 or the products of the same mould.

A still further and important object of the invention resides in the provision of a rerailer having relatively long and wide oppositely disposed inclines for allowing ready 35 movement of the wheels upwardly over the inclines, and having an arrangement of guide grooves so disposed at the higher point of intersection of the inclines as to cooperate with similarly formed grooves of 40 the companion rerailer as to positively guide the wheels into position upon each rail.

Other objects and advantages of the invention will be apparent during the course of the following detailed description, taken 45 in connection with the accompanying drawings, forming a part of this specification and in which drawings:

Figure 1 is a plan view of a section of track and showing a pair of the improved 50 rerailers in position and associated with the rails in a manner whereby the wheels of a piece of rolling stock may be guided into position upon the rails from either side of the rerailers.

Figure 2 is an enlarged end elevation of

one of the devices shown associated with a rail.

Figure 3 is a perspective view looking at the rerailer from its inner side or that side intended to be disposed adjacent the rail. 60

Figure 4 is a bottom plan view of the rerailer.

Figures 5, 6 and 7 are enlarged transverse sections on the respective lines of Figure 3. Referring to the drawings in detail, and 65 wherein similar reference characters designate corresponding parts throughout the several views, the numerals 5 and 6 may designate a pair of rails supported upon the cross ties or sleepers 7, and 8 may designate the 70 improved rerailer as a whole, and one of which has been shown associated with each of the rails 5 and 6 in a manner whereby the rerailers will co-act with one another to guide the wheels into position upon the 75 rails.

Referring now to the specific formation of the rerailers 8, the same are preferably formed of such length as to bridge at least three of the ties 7 and are of such width 80 at their ends as to prevent possible tilting of the devices during movement of the wheels up the inclined surfaces thereof. By observing Figure 1 it will be seen that the rerailers associated with each of the rails 85 5 and 6 and are of identical construction and are intended to be associated with like sides of the rails, that is, one rerailer is disposed at the inner side of the rail 5 while the co-acting rerailer is disposed at the outer 90 side of the rail 6. By observing Figure 2, it will be seen that the rerailer at its central highest portion is of a height greater than that of the rail 6.

The rerailer comprises an elongated body 95 portion 9 having a straight inner wall 10 and an outer wall 11 of substantially V-shape for forming a pair of oppositely inclined runways 12 being of greatest width at the ends of the body and converging to 100 a point at the transverse center or crown 13 of the body. These oppositely inclined slopes or runways 12 merge into relatively thin edges at each end of the body for allowing the wheels of the rolling stock to 105 readily pass upward over the runways. The body is preferably of hollow formation at its under side for reducing the weight of the rerailer, and a series of transverse webs 14 connect the inner and outer walls 10 and 110

11 respectively beneath the runways 12 to sufficiently reinforce the body, and it is preferred that the terminally disposed webs have openings 15 provided therein to provide hand holds for allowing easy handling of the rerailers.

Suitable projections 16 are provided at the under side of the body and preferably adjacent each end thereof for engagement 10 in the ties 7 for preventing longitudinal movement of the rerailers when being used. Suitable openings as at 17 may also be provided for allowing spikes to be driven thru the body into the cross ties when such becomes necessary to prevent longitudinal movement.

Extending or projecting upwardly at the outer edge of the runways 12 above the outer wall 11, is a guide flange 18 which extends 20 from the terminal portions of the body with its apex arranged at the transverse center of the body at the crown 13 forming the juncture of the oppositely inclined runways 12. Thus it will be seen that the guide flange 18 at its terminal portions is spaced further from the straight inner wall 10 than that of the medial portion of the flange so 25 that the flange of a wheel when engaging the guide flange at the outer end of one of the runways 12 will be guided by the guide flange toward the inner wall 10.

Projecting inwardly from the transverse center or crown 13 of the body portion 9 from the upper edge of the inner wall 10 35 is a retaining or rail engaging portion 20 having a flat under surface for resting upon the tread surface of the ball of the rail, and provided at its inner edge with a depending portion 21 which is intended to engage the side of the ball of the rail at the opposite side from which the body portion 9 is disposed. The upper surface of the overlying portion 20 conforms to the shape of the crown portion 13 and has its end edges 40 merging into the flat under side of the overlying portion so that the ends of the overlying portion will present no shoulders from which the wheels must drop when passing from the rerailer into position upon the rails.

Formed in the upper face of the runways 12 and extending parallel with the angular portions of the guide flange 18, are guide channels 25 which terminate at their upper or adjacent ends short of the crown 13 as 55 is clearly illustrated in Figures 1 and 3. These guide channels 25 at their lower ends merge into the surfaces of the runways 12 at a point substantially midway of the length of the runways and have their higher or upper ends extending past the inner edge of the body 9 and terminating in spaced relation in the overlying portion of the rail engaging portion 20.

60 Formed in the upper surface of the re-

taining portion 20 and extending from end to end thereof, is an inner arcuate-shaped guide groove 28 the crown portion of which extends toward the apex 29 of the substantially V-shaped guide flange 18 and the terminal portions of which open at the ends of the retaining portion above the depending portion 21. This inner arcuate-shaped guide groove 28 is disposed wholly upon the retaining portion 21 and does not communicate with the inner ends of the guide channels 25, there being a rib 30 retained between the inner end of the guide channels and the inner guide groove. Thus it will be seen that the inner guide groove 28 has its intermediate portion curved away from the depending portion 21 of the rail engaging portion 20 with the crown of the arcuate-shaped groove disposed at the crown 13 of the body portion 9 and spaced slightly from the inner ends of the guide channels 25.

Formed in the upper surface of the body portion 9 and extending across the crown 13 of the body portion, is an outer arcuate-shaped guide groove 32 the crown portion 90 of which extends into close proximity with the apex 29 of the guide flange 18 and the terminal portions of which communicate one with each of the longitudinal guide channels 25 at each side of the crown 13 and 95 preferably at a point adjacent the terminals of the rail engaging portion 20. This outer guide groove 32 is arcuated in a like direction to that of the inner arcuate-shaped guide groove 28 and has its terminal portions 100 merging into the guide channels 25 at a point intermediate the ends of the guide channels and outwardly of the inner edge of the body portion 9 or upon the surfaces outlined by the inclined runways 12. Referring particularly to Figure 5 showing a fragmentary section thru the crown portion of the rerailer, it will be seen that the inner inclined surface 18' of the guide flange 18 105 merges at its lower edge into the crown portion of the outer arcuate-shaped guide groove 32 in a manner whereby the wheel flange moving along the inclined surface 18' will be positively guided into the guide groove when the wheel reaches the crown 13 110 of the body portion 9. In other words, it 115 may be stated that the outer slope of the crown portion of the outer guide groove 32 merges into the lower portion of the inclined surface 18' at the crown 13 of the body portion 9.

In applying the rerailers to a rail, the inner wall 10 is intended to rest at its lower edge upon the base flange of the rail and for this reason the inner portion of the body portion 9 is recessed as at 34 so as to allow the outer portion of the body portion to rest flat upon the cross ties 7.

Referring particularly to Figure 1 and 120 wherein the dot and dash lines designated 130

A and B have been shown to illustrate the paths taken by the flanges of the wheels when being replaced upon the rails 5 and 6, it will be noted that the path B illustrates the path taken by the wheel which has to cross the rail 6 for disposing the flange of the wheel at the inner side of the rail. The arrows designate the direction of travel of the wheels upwardly over the rerailers into position upon the rails. As the wheels are moved forwardly, the flange of one wheel will engage the inner side of the guide flange 18 in the path A, and as the wheels move upwardly over the inclined runways 25 the flange of the path B will be guided into longitudinal guide channel 25 of the rerailer associated with the rail 6 by reason of the flange of the wheel taking the path A being shifted transversely by the angular guide flange 18. As the flange taking the path B moves to the upper end of the channel 25 and moves over the rib 30 into the inner arcuate-shaped guide groove 28, the wheel flange of the path A will have moved to the crown 13 and then directed by the inclined flange surface 18' into the crown portion of the outer guide groove 32. The wheel flanges are then guided in arcuate paths by the arcuate-shaped guide grooves into a position whereby the flange of the path B will be guided by the guide groove 28 to a position inwardly of the rail 6 while the flange of the path A will be guided to a position inwardly of the rail 5. The object in so having the rib 30 formed between the inner guide groove 28 and upper ends of the channels 25 is to prevent the possibility of the flange travelling the path B from entering the channel as at X in Figure 1 after the flange has once moved into position within the arcuate guide groove 28. By so having the terminal portions of the outer arcuate-shaped guide groove 32 opening into the guide channels 25 it will be seen that the wheel flange taking the path A will be readily guided to a position inwardly of the rail 5 by reason of its passing at the end of the groove 32 into the channel 25 as at Y in Figure 1. The wheels will be prevented from dropping upon the tread surfaces of the ball of the rails by reason of the fact that the flange taking the path B is directed across the rail 6 in angular relation to the rail, and the flange taking the path A will ride down the incline 25 from the point Y until the rim of the wheel engages the tread surface of the rail 5.

From the foregoing description it will be apparent that an improved construction for rerailers has been provided wherein a pair of the devices may be used for replacing the wheels of rolling stock, and which devices are of such construction as to allow for two of the devices of identical construction being used for positive replacing of the wheels

upon the rails without likelihood of the wheels dropping from the rerailer after being elevated to a position above the rails. It will further be apparent that a novel arrangement of guide grooves and channels has been formed upon the inclined runways of the rerailer for forming positive paths for the flanges of the wheels whereby the flanges are positively guided into position at the proper side of the rails upon which the wheels are being mounted.

Changes in detail may be made to the specific form of the invention herein shown and described, without departing from the spirit of the invention or the scope of the following claims.

I claim:

1. A rerailer comprising an elongated body portion having oppositely inclined runways provided at its upper surface forming a transverse crown, an upstanding guide flange extending along the outer edge of the body portion from end to end thereof, a rail engaging portion projecting inwardly from the body portion at the crown formed by the oppositely inclined runways, guide channels formed longitudinally in the runways at each side of the crown, a guide groove connecting said guide channels and traversing the crown, and a second guide groove formed in the upper surface of the rail engaging portion and opening at each end thereof at the inner edge of the portion.

2. A rerailer comprising an elongated body portion having oppositely inclined runways provided at its upper surface forming a transverse crown, said runways flaring toward each end of the body portion, an upstanding guide flange extending along the outer edge of the body portion and converging toward said crown, a rail engaging portion projecting inwardly from the body portion at the crown and having its upper surface conforming to the upper surface of the body portion, guide channels formed longitudinally in the runways in parallel relation with the angular portion of the guide flange at each side of the crown, a guide groove connecting said guide channels and traversing the crown, and a second guide groove formed in the upper surface of the rail engaging portion and extending from end to end thereof with the terminals of the guide groove opening at the inner edge of the rail engaging portion.

3. A rerailer comprising an elongated body portion having oppositely inclined runways provided at its upper surface forming a transverse crown, said runways flaring from the crown toward each end of the body portion, an upstanding guide flange extending along the outer edge of the runways and converging to the crown, a rail engaging portion projecting inwardly from the body portion at the crown and having its upper

surface conforming to the upper surface of the body portion, guide channels formed longitudinally in the runways at each side of the crown and terminating in spaced relation at their upper ends in the rail engaging portion, an arcuate-shaped guide groove connecting said channels at opposite sides of said crown with the guide groove arcuated toward the apex of the angularly disposed portions of the guide flange, and a second guide groove formed in the upper surface of the rail engaging portion and arcuated in a like direction to that of said first mentioned arcuate guide groove and opening at each end of the rail engaging portion adjacent the inner edge of the portion.

4. A rerailer comprising an elongated body portion having oppositely inclined runways provided at its upper surface forming a transverse crown, said runways having their outer edges converging toward said crown, an upstanding guide flange extending along the outer edge of the body portion and having portions converging toward said crown, said guide flange having an inclined inner surface, a rail engaging portion projecting inwardly from the body portion at the crown and having its upper surface conforming to the upper surface of the body portion, an inner arcuate-shaped guide groove formed in the upper surface of the rail engaging portion, guide channels formed longitudinally in the runways at each side of the crown and having their upper ends terminating short of the inner guide groove, and an outer arcuate-shaped guide groove connecting said guide channels at opposite sides of the crown with the crown portion of the outer guide groove extending into close proximity with the inner inclined surface of the guide flange at said crown.

5. A rerailer comprising an elongated body portion having oppositely inclined runways provided at its upper surface forming a transverse crown, said body portion having a straight inner side and having its outer sides converging toward the crown whereby said runways flare toward each end of the body, an upstanding guide flange extending along the outer edge of the body portion with its apex arranged at the crown of the body portion, said guide flange having an inclined inner face, a rail engaging portion projecting inwardly from the body portion of the crown and having its upper

surface conforming to the oppositely inclined runways, an inner arcuate-shaped guide groove provided in the upper surface of the rail engaging portion and extending from end to end thereof, said guide groove being arcuated toward the outer edge of the body portion, guide channels formed longitudinally in the runways at each side of the crown and terminating in spaced relation at their upper ends closely adjacent the crown of the inner guide groove, and an outer arcuate-shaped guide groove connecting the guide channels at opposite sides of the crown of the body portion, said outer guide groove being arcuated toward the outer edge of the body portion and having its crown portion sloping upwardly into the lower portion of the inner inclined wall of the guide flange at the apex portion of the guide flange.

6. In a rerailer, a body portion having an inclined runway provided at its outer edge with an upstanding guide flange, a rail engaging portion projecting inwardly from the body portion at the upper end of the runway, a guide groove formed in the upper surface of the rail engaging portion and opening at the ends of the portion, and a guide channel formed longitudinally in the runway and having its upper end terminating short of the guide groove.

7. In rerailing apparatus for railway rolling stock, a pair of rerailing members for positioning longitudinally one at the inner and the other at the outer sides of opposite rails, said inner disposed member including an elongated body portion provided with an inclined runway extending above the tread surface of the rail, a guide flange extending along the outer edge of the runway in converging relation to the rail, and a guide groove extending from the upper end of the flange and opening at the inner edge of the member, and said outer disposed member including an elongated body portion provided with an inclined runway extending to a position above the tread surface of the rail, a rail connecting portion extending in overlying relation to the tread surface of the rail, a guide channel formed longitudinally in the runway and converging toward the rail at the upper end of the runway, and a guide groove formed in the upper surface of the rail engaging portion and opening to the inner side of the rail with which the rerailing member is associated.

CLARENCE C. SCOTT.
